UNITED STATES PATENT OFFICE.

SYLVANUS D. LOCKE, OF HOOSICK FALLS, NEW YORK.

SELF-CLOSING GAS-BURNER.

SPECIFICATION forming part of Letters Patent No. 357,840, dated February 15, 1887.

Application filed July 31, 1886. Serial No. 209,658. (No model.)

To all whom it may concern:

Be it known that I, SYLVANUS D. LOCKE, a citizen of the United States, residing at Hoosick Falls, in the county of Rensselaer and State of New York, have invented certain new and useful Improvements in Self-Closing Gas-Burners, of which the following is a full, clear, and exact description.

My invention consists in certain features of construction hereinafter specified, and particularly pointed out in the claims.

In the drawings, Figure 1 is a front view or elevation of a burner with my improvements attached. Fig. 2 is a top view of the same, but showing nothing of the burner below the line *x y*, Fig. 1. Fig. 3 is a perspective view showing how the bars, lever, and support are connected. Fig. 4 is a perspective view of a portion of the burner, showing the pawl pushed back by the lever as the bars are expanded by the heat and the cock locked on the shoulder of the lever; and Fig. 5 is a top view of the parts shown in Fig. 4.

A is the base-section, to which is attached the burner B. C is the burner-tip, D the gas-pipe to which the base A is attached, and E is the handle and F the stem of the shut-off cock.

Sleeved on the burner and firmly secured thereto is the support *a*, having opposing lateral and upward-extending arms. To the end of one of these arms the lever *c* is fulcrumed, while the bars *b* join the lever to the other arm of the support. I prefer to use two bars; but only one is required. These bars should pass on either side of and close to the flame, and the slot in the tip C should be parallel to the bars, as shown in Fig. 2.

Attached to the base A is a pawl, *d*, pivoted at *d'*, that is held by a spring, *e*, normally against a stop, *f*. This pawl has a ratchet-shaped ledge or shoulder at its end, as shown. The shut-off cock F is closed by the spring *g*, and is locked open by means of the radial pin or projection *i*. As the cock is opened by the finger-piece or handle E, this pin *i* drives back the pawl and is caught on the hook or ledge at its lower end, where it is temporarily held until the expansion of the bars *b* swings the lever *c* on its fulcrum until its lower end crowds

back the pawl from underneath the pin *i*, when 50 the latter, released from the pawl, is caught on the hook at the end of the lever *c*, where it remains until the extinguishment of the flame causes the bars *b* to contract and so swing back the lever until the hook or catch at its lower 55 end is withdrawn from underneath the pin *i*, when the cock is closed by the action of the spring *g*.

To prevent the heat from extending from the bars to the support, and so partly neutralizing the expansion of the bars, I insert between the bars and the support and the bars and the lever, at their pivot-points, washers *h*, of some poor heat-conducting material, as asbestos-cloth or paper. 65

What I claim is—

1. In a self-closing gas-burner, the combination, with the cock, a radial pin, and a closing-spring, and with the burner provided with a yoke, of an expansion-bar and a detent-pawl pivoted to the burner and yieldingly pressed toward the pin, and a releasing-lever pivoted to the yoke and to the expansion-bar, having its free end arranged in a common vertical plane with the detent, substantially as 75 specified.

2. In a self-closing gas-burner, a cock, a radial pin, and a closing-spring, a yieldingly-pressed detent suspended from the base of the burner and in a vertical plane, with a releasing-detent, a yoke, and an expansion-bar, and a releasing-detent suspended vertically from the yoke, substantially as specified. 80

3. In a self-closing gas-burner, a cock, a closing-spring, and a radial pin, in combination with a suspended spring-pressed detent pivoted to the base of the burner, a yoke mounted upon the burner and supporting an expansion-bar and in substantially the same vertical plane with the cock, and a release-detent pivoted to 85 the yoke and suspended in the same vertical plane as and constructed to release the spring-pressed detent by the expansion of the bar, substantially as specified. 90

SYLVANUS D. LOCKE.
